Primary Examiner — Vy N Koenig*Assistant Examiner* — Qiawen W Wiechert(74) Attorney, Agent, or Firm — Young Basile Hanlon & MacFarlane, P.C.(57) CLAIM

The ornamental design for a modular structure as shown and described.

DESCRIPTION

The sole FIGURE is a perspective view of a modular structure comprising multiple panels, showing the new design.

The broken lines and areas within the broken lines depict environmental subject matter, specifically a fire pit, that forms no part of the claimed design.
